UNITED STATES PATENT OFFICE.

HELEN LOUISE RAY, OF LOS ANGELES, CALIFORNIA.

ORNAMENTATION FOR WASH DRESSES.

Application filed February 23, 1927. Serial No. 170,252.

This invention relates to novel means for ornamenting wash dresses made of bright colored materials, and which ornamentation will give to such a dress or frock the highest 5 degré of style.

An object of my invention is to provide a novel combination, whereby patent leather, or what is known as oil cloth, which is generally understood to be nonwashable in the 10 same sense as clothes, may be used in combination with a dress made of washable material and to permit such dress to be washed without the necessity of subjecting the ornamentation to the liquid in which the 15 dress is washed.

Another object is to provide a novel ornamentation for wash dresses and which will give the greatest amount of style or "dress" to such wash dress.

20 Another object is to provide novel means for ornamenting a house dress and which ornamentation means may be useful in giving to such dress the greatest amount of ornamentation or contrast, and which is 25 also useful to the wearer as a pocket.

I have discovered that a Japanese crepe wash frock is greatly enhanced in beauty by the addition of patent leather trimmings thereto whereby all of the vivid coloring of 30 such wash frock is brought out with the result that a very smart and serviceable dress, suitable for wear at the beaches, summer vacationing, or wherever a wash dress is desirable, may be produced.

35 Other objects, advantages and features of invention may appear from the accompanying drawing, the subjoined detail description, and the appended claims.

The accompanying drawing illustrates the 40 invention in some of the forms I at present deem preferable.

Figure 1 is a front view of a dress to which my novel ornamentation is secured.

45 Figure 2 is a fragmental front view of a dress provided with a slightly different form of ornamental means.

Figure 3 is a side view on a slightly enlarged scale, of the device shown in Figure 2.

50 Figure 4 is a view showing the detailed pocket and belt construction shown in Figures 2 and 3, and

55 Figure 5 is a similar view but showing the pocket and belt construction shown in Figure 1.

My invention comprises the combination of a frock or dress 1 made of washable material, and ornamented or provided with ornamental means 2, such as ornamental or imitation pockets or the like, which may be 60 merely imitation pockets used solely for ornamental purposes, or which may be used as a pocket. The ornamentation means 2 for the dress 1 is preferably made of patent leather, such as oil cloth which is not ordinarily washable in the same sense as a wash dress, but which has been found, when added to vividly colored or brightly colored crepe, or other wash dresses, that all of the beauty 65 and coloring of the material from which the 70 dress is made, is brought out in all its vivid colors.

By this combination I am able to provide an inexpensive wash dress that will display its colors to the highest degree by reason of contrasting such color with the effects 75 only obtained from patent leather. The ornamentation 2 is adapted and arranged so as to be easily and quickly detached from, or attached to, the dress 1, as desired. 80

In Figures 1 and 5 I have shown pockets 3 that have a body portion *a* provided with extension members 4 extending upwardly from each side of the pocket 3 and which extensions 4 are provided with holding 85 straps that are formed by slitting the extension 4 so as to provide a slot 5 that is adapted to receive the belt 6 which is of sufficient length to encircle the waist line of the wearer and to be secured in position by 90 any suitable fastening means, such as the button 7 and buttonhole 8.

By the arrangement hereinabove described I am able to trim a wash dress that may be made of any washable material in a highly 95 artistic and desirable manner, with a material not ordinarily washable such as patent leather. It will be apparent that such dress may be worn with or without such ornamentation. When it is desired to use my novel 100 ornamentation means in combination with a wash dress, such means may be easily and quickly secured thereto near the waist line thereof and is detachably fastened to the dress by merely securing together the ends of the belt 6. The pockets 3 are preferably arranged so as to depend from the belt 6 at 105 the sides of the dress.

The ornamentation means 2' shown in Figures 2, 3 and 4 comprises a body encir- 110
